(57) **CLAIM**

The ornamental design for an electrical fitting for non-metallic electrical cable, as shown and described.

DESCRIPTION

FIG. 1 is a top, front and right side exploded perspective view of an electrical fitting for non-metallic electrical cable, which consists of a cable securing device portion attaches to a main body portion, showing my new design;

FIG. 2 is a top, front and right side perspective view thereof, in an assembled condition;

FIG. 3 is a top plan view thereof;

FIG. 4 is a left side elevation view thereof;

FIG. 5 is a bottom plan view thereof;

FIG. 6 is a rear perspective view thereof;

FIG. 7 is a right side elevation view thereof;

FIG. 8 is a rear elevation view thereof;

FIG. 9 is a front elevation view thereof;

FIG. 10 is a top plan view thereof, in use condition.

FIG. 11 is a front perspective view of a cable securing device portion forming part of the electrical fitting;

FIG. 12 is a rear perspective view thereof;

FIG. 13 is a rear elevation view thereof;

FIG. 14 is a front elevation view thereof;

FIG. 15 is a right side elevation view thereof, the left side elevation view being a mirror image thereof; and,

FIG. 16 is a top plan view thereof, the bottom view being a mirror image thereof.

The broken line in the figure drawing views is included for the purpose of illustrating unclaimed environment and forms no part of the claimed design.

1 Claim, 8 Drawing Sheets
